INTERNAL COMBUSTION ENGINE

Filed June 3, 1926

UNITED STATES PATENT OFFICE

EMILE PAUL DUMANOIS, OF BOULOGNE-SUR-SEINE, FRANCE, ASSIGNOR, BY MESNE ASSIGNMENTS, TO MAXMOOR CORPORATION, OF NEW YORK, N. Y., A CORPORATION OF DELAWARE

INTERNAL-COMBUSTION ENGINE

Application filed June 3, 1926, Serial No. 113,392, and in France May 17, 1926.

It is well known that the volumetric compression in internal combustion engines is limited by the so-called "detonation", which is caused by an actual explosive wave.

5 However, in order to provide for a high compression of the fuel mixture affording great advantages from an economical standpoint, substances commonly termed anti-detonating substances have been employed, acting by their chemical properties and serving to delay the formation of the explosive wave. But in view of the fact that this wave is of both a physical and a chemical nature, I have found that the desired result can be attained 15 by merely physical methods and that anti-detonating substances may be dispensed with.

My invention has accordingly for its object to provide means, acting in a physical manner, for obviating such an explosive effect.

When an explosive wave proceeds through a conduit, it is well known that said wave may be readily stopped by simply increasing the cross-section of the conduit, the detonation being replaced by a regular combustion; after a certain time, this may be followed anew by an explosive wave, if the section of the conduit remains constant or decreases.

It is further observed that, under similar 33 conditions, an increase of the surface of the combustion chamber will produce a greater cooling of the gas, whereby the limit of compression at which the detonation takes place, as well as the limit of self-ignition by compression, will be set back.

With the above observations as a basis, I have been enabled to provide a combustion chamber by which the desired object is attained.

40 For this purpose, the cross section of the combustion chamber increases in the direction of propagation of the inflammation, and the increase in the section may be continuous or intermittent; the surface of the walls is 45 relatively large, so as to obviate the explosive wave which tends to be produced, or to stop the propagation of such waves.

The appended drawing shows by way of example, various embodiments of the invention.

Figs. 1, 2 and 3 are respectively sections on the line I—I of Fig. 2, II—II of Fig. 3, and a front view, of the first embodiment, with the piston at the upper dead centre. Fig. 4 is a front view of a modification. Figs. 5 and 6 are vertical axial sections of further modifications. Fig. 7 is a section on the line VII—VII of Fig. 6.

As shown in Figs. 1 to 4, the ignitor is disposed at 1 in the cylinder 2, and, at its upper end, the piston is formed with a head or projecting part 4, whose upper face comes near the cylinder head when the piston is at the upper dead centre, as shown in the drawing. The head is cut out to form a cylindrical recess 6 through a suitable length, according to the direction of propagation of the inflammation. In the plane B—B, the offsets 7 causing an abrupt enlargement of the combustion chamber, both by the increase of cross section of the cylindrical recess and by the lowering of the level of the upper face of the head 4, which proceeds from 5 to 8. Like variations in the section of the cylindrical recess and in the lowering of the level of the upper face of the head 4 will take place in the planes C—C, D—D, E—E, by the formation of transverse offsets 9, 10, 11 and vertical offsets 12, 13, 14.

The operation is as follows:

The inflammation begins at 1, and proceeds at a certain velocity the piston still raising, thus reducing the volume and facilitating the production of an explosive wave; when the inflammation attains a point near the section B—B, however the section is abruptly enlarged, causing an expansion by which the wave which might have been produced will be stopped. The same is true when the inflammation reaches the section C—C, then the section D—D, and finally the section E—E.

From the foregoing it will be seen that the different offsets formed in the piston, starting from the point of ignition will produce, as the inflammation attains the respective offsets, suitable expansions which will prevent the propagation of the explosive wave.

The above constructional details are given solely by way of example, and I may obtain the same effect, in other cases, by a construc-

tion in which the offsets at the top of the piston are eliminated or exist only upon a certain part of the head and on either side of the plane of symmetry or in which the lower generatrices of the successive cylindrical recesses 5 form offsets by proceeding from one recess to the next (Fig. 4), instead of being all at the same height, as in Figs. 1 to 3, or otherwise the offsets are formed only upon the upper 10 face of the piston, the cylindrical recesses in the piston head being dispensed with.

In the foregoing and also in the following explanations, I employ for the sake of clearness, the term "cylindrical" to designate the 15 outline of the successive recesses, but it should be noted that the invention is not restricted to cylindrical surfaces in the geometrical sense of the word, but relates to surfaces of a substantially cylindrical shape, or even to conical, spherical or like surfaces, provided that the cross-sections are progressively larger in 20 the direction of propagation of the inflammation.

Moreover, the term "offset" relates to regions of abrupt augmentation of the cross section, but the walls may be either plane or curved, and suitably inclined and connected together.

The number of offsets may be increased at 30 will, either upon the whole or upon a part of the piston surface, in the direction of propagation of the flame, the whole or a part of the offset's being thus replaced by a continuous surface such that the cross section is progressively larger.

In case the valves are laterally disposed or with engines with sleeve valves or engines of the two-stroke type, the offsets or the surfaces connecting two successive sections of increasing cross-section may be provided solely upon 40 the piston (as in the preceding case) or solely upon the end of the cylinder, or both upon the end of the cylinder and the end of the piston.

In the preceding constructions, the ignitor 45 is situated upon the side wall of the cylinder. Arrangements based upon the same principle may be provided in case the ignition device is mounted on the cylinder head, for instance at the centre thereof.

50 Figs. 5 to 7 show, by way of example, a piston construction which may be employed in this case, the ignitor being situated at 20. The offsets now consist of circular or other projections and the planes B—B, C—C, 55 D—D, E—E of Figs. 1 to 4 are replaced by the cylindrical or other surfaces B¹ C¹ D¹ E¹ which form the required offsets on the end of the piston. The operation is the same as before. By increasing the number of offsets 60 upon the whole or a part of the piston surface, I may obtain, in the limit, a piston surface which will be wholly or partially continuous, as above indicated.

When side valves are employed, or when the 65 engine is of the sleeve-valve or the two-stroke

type, the offsets, or surfaces connecting parts of increasing section, may be situated either on the end of the piston or on the end of the cylinder 15, or on the end of the piston and the end of the cylinder, as shown in Fig. 6.

When the engine comprises several ignitors, the increase in the sections will take place (as above indicated) in the direction of propagation of the flame, starting from the different ignition points.

In the various embodiments hereinbefore described, I further obtain a material increase of the surface of the chamber in contact with the fuel mixture relatively to the constructions in current use, and hence an increased cooling 75 of the gas, by which the risk of detonations and self-ignition by compression will be diminished.

Having now described my invention, what I claim as new and desire to secure by Letters 80 Patent is:

1. An internal combustion engine comprising opposing portions forming in the combustion chamber thereof a passage increasing in cross-section by abrupt steps from one 90 point thereof to another, and ignition means disposed within said combustion chamber adjacent to the more constricted portion of said passage.

2. An internal combustion engine comprising opposing portions in the combustion chamber thereof each having surfaces disposed in offset relation, and forming a passage therebetween increasing in cross-section from the ignition point in the direction of 95 propagation of the inflammation.

3. An internal combustion engine comprising opposing portions of the combustion chamber, and ignition means disposed in said combustion chamber; certain of said portions including a step formation having certain of the surfaces thereof disposed transversely of the direction of propagation of the inflammation, and facing the portion of said combustion chamber remote from said ignition 100 means.

4. An internal combustion engine comprising opposing portions forming a combustion chamber of increasing cross-section, and ignition means in the more constricted portion of said combustion chamber; certain of said opposing portions consisting of a step formation having certain of the surfaces thereof disposed transversely of the direction of propagation of the inflammation and facing the enlarged portion of said combustion 110 chamber.

5. An internal combustion engine comprising a combustion chamber ceiling of step formation forming with an opposite portion of the combustion chamber a passage increasing in cross-section from the ignition point in the direction of propagation of the inflammation.

6. An internal combustion engine compris-

ing the ceiling of the combustion chamber and a piston, each having a plurality of surfaces disposed in offset relation to each other, and the same providing therebetween a passage 5 increasing in cross-section by abrupt steps.

7. An internal combustion engine comprising a combustion chamber ceiling having surfaces of step formation forming a projection in spaced relation to the lateral wall portions of the combustion chamber and providing 10 an outwardly flaring recess about said projection.

8. An internal combustion engine comprising a portion of the ceiling of the combustion chamber having a recess about the spark plug provided with surfaces of step formation, and a piston having a projection into the combustion chamber, and provided with surfaces 15 of step formation.

9. An internal combustion engine comprising a cylinder having a combustion chamber at the end thereof, and a piston in said combustion chamber; said piston and the ceiling of the combustion chamber including tapering 20 portions of step formation projecting towards each other, and providing a space about the same increasing in cross-section outwardly therefrom.

10. An internal combustion engine comprising 30 a portion of step formation having in exposed relation to the interior of the combustion chamber transversely extending step surfaces disposed in successive planes in substantially off-set relation to each other and vertically extending riser surfaces connecting the step surfaces; the combustion chamber space contiguous to said step and riser surfaces abruptly varying in cross-section in accordance with the variations in location of 35 said step surfaces, and ignition means in said combustion chamber disposed to cause propagation of the inflammation therefrom through said space over said step and riser surfaces.

11. An internal combustion engine comprising 45 a portion of step formation projecting into the combustion chamber and having in exposed relation to the interior of the combustion chamber transversely extending step surfaces disposed in successive planes in substantially off-set relation to each other, and vertically extending riser surfaces connecting the step surfaces; the combustion chamber space contiguous to said step and riser surfaces varying in cross-section in accordance with the variations in location of said step surfaces, and ignition means in said combustion chamber disposed to cause propagation 55 of the inflammation therefrom through said space over said several step and riser surfaces.

12. An internal combustion engine comprising 60 a portion of step formation projecting into the combustion chamber thereof and having in exposed relation to the interior

of the combustion chamber transversely extending step surfaces disposed in successive planes in substantially off-set relation to each other and vertically extending riser surfaces connecting the step surfaces; the combustion 70 chamber space contiguous to said step and riser surfaces progressively increasing in cross-section by abrupt steps, and ignition means adjacent to the more constricted portion of said space for causing the inflammation 75 to be propagated over said step and riser surfaces towards the enlarged portion of said space.

13. An internal combustion engine comprising a portion of step formation projecting into the combustion chamber in spaced relation to the lateral wall portion thereof; said projecting portion having in exposed relation to the interior of the combustion chamber transversely extending step surfaces disposed 80 in successive planes in substantially off-set relation to each other and vertically extending riser surfaces connecting the step surfaces; the combustion chamber space contiguous to said step and riser surfaces varying 85 in cross-section in accordance with the variations in location of said step surfaces, and ignition means in said combustion chamber disposed to cause the inflammation to be propagated therefrom through said space 90 over said several step and riser surfaces.

14. An internal combustion engine comprising 95 ignition means in the combustion chamber thereof, and a portion of step formation projecting into the combustion chamber in spaced relation to the lateral wall portions thereof; said projecting portion having in exposed relation to the interior of the combustion chamber transversely extending step surfaces disposed in successive planes in 100 substantially off-set relation to each other and vertically extending riser surfaces connecting the step surfaces; the combustion chamber space contiguous to said step and riser surfaces increasing in cross-section in the direction of propagation of the inflammation. 105

15. An internal combustion engine comprising 110 a portion of step formation in the combustion chamber thereof; said portion having in exposed relation to the interior of the combustion chamber transversely extending annular step surfaces disposed in successive planes in substantially off-set relation to each other and vertically extending riser surfaces connecting the step surfaces; and the combustion chamber space contiguous to said step and riser surfaces varying in cross-section by abrupt steps in accordance with the variations in location of said step surfaces, and ignition means in said combustion 115 chamber disposed to cause propagation of the inflammation therefrom through said space over said several step and riser surfaces.

16. An internal combustion engine comprising 120 a portion of step formation in the

combustion chamber thereof; said portion having in exposed relation to the interior of the combustion chamber transversely extending annular step surfaces disposed in successive planes in substantially off-set relation to each other and vertically extending riser surfaces connecting said step surfaces; and said step and riser surfaces providing a combustion chamber space increasing in cross-section by abrupt steps, and ignition means adjacent to the more constricted portion of said combustion chamber.

17. An internal combustion chamber comprising a portion of step formation projecting into the combustion chamber thereof in spaced relation to the lateral wall portions thereof; said portion of step formation having in exposed relation to the interior of the combustion chamber transversely extending annular step surfaces disposed in successive planes in substantially off-set relation to each other and vertically extending riser surfaces connecting the step surfaces; and said step and riser surfaces providing a combustion chamber space increasing in cross-section by abrupt steps, and ignition means adjacent to the more constricted portion of said space.

18. An internal combustion engine comprising a portion of step formation projecting into the combustion chamber thereof in spaced relation to the lateral wall portion thereof; said portion of step formation having in exposed relation to the interior of the combustion chamber transversely extending annular step surfaces disposed in successive planes in substantially off-set relation to each other and vertically extending riser surfaces connecting the step surfaces; and said step and riser surfaces providing a combustion chamber space increasing in cross-section outwardly by abrupt steps, and ignition means disposed axially relative to said projecting portion.

19. An internal combustion engine comprising a cylinder having a combustion chamber at the end thereof, a piston in said cylinder, and a step formation on the head thereof having in exposed relation to the interior of the combustion chamber transversely extending step surfaces disposed in successive planes in substantially off-set relation to each other and vertically extending riser surfaces connecting said step surfaces; the combustion chamber space contiguous to said step and riser surfaces abruptly varying in cross-section in accordance with the variation in location of said step surfaces, and ignition means in said combustion chamber disposed to cause propagation of the inflammation therefrom through said space over said several step and riser surfaces.

20. An internal combustion engine comprising a cylinder having a combustion chamber at the end thereof, a piston in said cylinder,

der, a step portion on the head thereof having in exposed relation to the interior of the combustion chamber transversely extending step surfaces disposed in successive planes in substantially offset relation to each other and vertically extending riser surfaces connecting said step surfaces; the combustion chamber space contiguous to said step and riser surfaces increasing in volume by abrupt steps from the higher of said step surfaces to the lower thereof, and ignition means disposed within said combustion chamber adjacent to the more constricted portion of said space to cause the inflammation to be propagated therefrom over said several surfaces towards the relatively enlarged portion of said space.

21. An internal combustion engine comprising a cylinder having a combustion chamber at the end thereof, and a piston in said cylinder, a step portion on the head thereof increasing in height from the periphery towards the center of said piston head and projecting into said combustion chamber in spaced relation to the top and lateral wall portions thereof; said step formation including transversely extending step surfaces disposed in successive planes in substantially offset relation to each other and vertically extending riser surfaces connecting the step surfaces, and ignition means in said combustion chamber disposed to cause propagation of the inflammation therefrom over said several step and riser surfaces.

22. An internal combustion engine comprising a cylinder having a combustion chamber at the end thereof, a piston in said cylinder, and a step portion on the head thereof increasing in height from the periphery towards the center and forming with the wall portions of said combustion chamber a space increasing in volume by abrupt steps from the axis of said cylinder outwardly, and ignition means disposed on the wall of said combustion chamber axially of the cylinder adjacent to the more constricted portions of said space.

23. An internal combustion engine comprising a cylinder having a combustion chamber at the end thereof, a piston in said cylinder, and a formation on the head thereof increasing in height from the periphery towards the center and consisting of transversely extending step surfaces disposed in successive planes in substantially off-set relation to each other and vertically extending riser surfaces; said step and riser surfaces and the opposing wall portions of said combustion chamber providing a space therebetween increasing in volume by abrupt steps from the axis of said cylinder outwardly, and ignition means disposed on the wall of said combustion chamber axially of the cylinder adjacent to the more constricted portion of said space.

24. An internal combustion engine com-

- prising a step formation on the ceiling of the combustion chamber having in exposed relation to the interior thereof transversely extending step surfaces disposed in successive planes in substantially off-set relation to each other and vertically extending riser surfaces connecting the step surfaces; the combustion chamber space contiguous to said step and riser surfaces abruptly varying in cross-section in accordance with the variation in location of said step surfaces, and ignition means in said combustion chamber disposed to cause propagation of the inflammation therefrom through said space over said several step and riser surfaces.
25. An internal combustion engine comprising a step formation on the ceiling of the combustion chamber having in exposed relation to the interior thereof transversely extending step surfaces disposed in successive planes in substantially off-set relation to each other and vertically extending riser surfaces connecting the step surfaces; the combustion chamber space contiguous to said step and riser surfaces abruptly increasing in cross-section, and ignition means disposed adjacent to the more constricted portions of said space to cause propagation of the inflammation over said several step and riser surfaces towards the enlarged portion of said space.
26. An internal combustion engine comprising a step formation on the ceiling of the combustion chamber having transversely extending annular step surfaces disposed in successive planes in substantially off-set relation to each other and vertically extending riser surfaces connecting the step surfaces; said step and riser surfaces being exposed to and forming a combustion chamber space increasing in cross-section by abrupt steps, and ignition means adjacent to the more constricted portion of said space.
27. An internal combustion engine comprising a downwardly projecting step formation on the ceiling of the combustion chamber having in exposed relation to the interior thereof transversely extending step surfaces disposed in successive planes in substantially off-set relation to each other and vertically extending riser surfaces connecting the step surfaces; the combustion chamber space contiguous to said step and riser surfaces abruptly varying in cross-section in accordance with the variation in location of said step surfaces, and ignition means in said combustion chamber disposed to cause propagation of the inflammation therefrom through said space over said several step and riser surfaces.
28. An internal combustion engine a step formation on the ceiling of the combustion chamber projecting downwardly in spaced relation to the lateral wall portions thereof and having in exposed relation to the interior thereof transversely extending annular step surfaces disposed in successive planes
- in substantially off-set relation to each other and vertically extending riser surfaces connecting the step surfaces; the combustion chamber space contiguous to said step and riser surfaces abruptly varying in cross-section in accordance with the variation in location of said step surfaces, and ignition means in said combustion chamber disposed to cause propagation of the inflammation therefrom through said space over said several step and riser surfaces.
29. An internal combustion engine comprising a downwardly projecting step formation on the ceiling of the combustion chamber having in exposed relation to the interior thereof transversely extending annular step surfaces disposed in successive planes in substantially off-set relation to each other and vertically extending riser surfaces connecting the step surfaces; the combustion chamber space contiguous to said step and riser surfaces abruptly increasing in cross-section in accordance with the location of said step surfaces, and ignition means disposed adjacent to the more constricted portion of said space to cause propagation of the inflammation over said several step and riser surfaces towards the enlarged portion of said space.
- In testimony whereof I have signed my name to this specification.
- EMILE PAUL DUMANOIS.
